United States Patent Office.

WILLIAM MAGINN, OF NEW YORK, N. Y.

Letters Patent No. 77,062, dated April 21, 1868.

IMPROVEMENT IN PENCIL-CASES.

The Schedule referred to in these Letters Patent and making part of the same.

TO ALL WHOM IT MAY CONCERN:

Be it known that I, WILLIAM MAGINN, of the city, county, and State of New York, have invented new and useful Improvements in Pen and Pencil-Cases; and I do hereby declare that the following is a full, clear, and exact description thereof, which will enable those skilled in the art to make and use the same, reference being had to the accompanying drawings, forming part of this specification, in which—

Figure 1 is a side view of my improvements.

Figure 2 is a side view of the whalebone cylinder.

Figure 3 is a cross-section of the same.

Similar letters of reference indicate corresponding parts.

This invention consists in the employment of a cylinder, of whalebone, as shown at *a*, between the metal ends *b* of a pencil-case, whereby it serves to enclose the metal barrel, containing the mechanism for protruding the lead-holder *d*, and simulates the appearance of hard rubber, heretofore used, which material is expensive, and liable to crack in cold weather.

The whalebone is susceptible of a variety of ornamental configurations, and takes on a high polish, which is more durable than the polish on hard rubber.

The whalebone cylinders are bored out and turned off on a mandrel, and may be made, with the proper machinery, very rapidly, thereby lessening the cost of the complete pencil-cases.

Another important advantage of the whalebone is, that containing no sulphur, it does not oxidize the gold or silver ends of the case, as does the hard rubber, by reason of the sulphur contained therein.

I claim as new, and desire to secure by Letters Patent—

An article of manufacture, consisting of a pencil-case, having whalebone cylinders *a*, substantially as shown and described and for the purposes set forth.

The above specification of my invention signed by me, this 19th day of February, 1868.

WILLIAM MAGINN.
